UNITED STATES PATENT OFFICE.

WEBB JAY, OF CHICAGO, ILLINOIS.

FUEL-ELEVATING DEVICE FOR AUTOMOBILE-ENGINES.

1,132,940.

Specification of Letters Patent. Patented Mar. 23, 1915.

Application filed June 26, 1914. Serial No. 847,417.

To all whom it may concern:

Be it known that I, WEBB JAY, a citizen of the United States, residing at Chicago, in the county of Cook and State of Illinois, 5 have invented new and useful Improvements in Fuel-Elevating Devices for Automobile-Engines, of which the following is a specification, reference being had to the accompanying drawings, forming a part thereof.

10 The purpose of this invention is to provide a convenient and easily accommodated means for elevating the liquid fuel supply for an internal combustion engine of an automobile from a storage tank in the usual 15 low position, to a position from which it may be fed by gravity to the carbureter.

It consists in the elements and features of construction shown and described as indicated in the claims.

20 In the drawings: Figure 1 is a side elevation of a structure embodying this invention, shown in association with an automobile engine or parts thereof. Fig. 2 is a vertical section through the elevated receptacle and the vacuum-producing device. 25 Fig. 3 is a sectional view of a different form of pumping device showing different means of actuating the same.

In the structure shown in the drawings, 1 30 represents a receptacle for liquid fuel located at a position from which fuel may be fed by gravity to the carbureter indicated in dotted lines at 2.

3 is a diaphragm pump device comprising 35 a diaphragm, 4, suitably clamped between a flange, 5, at the margin of the chamber, 7, closed by the diaphragm and an exterior clamping ring, 6. The diaphragm is connected at its center by means of suitable 40 clamping disks, 8 and 8^a, to an operating lever, 9, which is actuated by a reciprocating rod, 9^a, terminating the eccentric strap, 10, of an eccentric, 11, mounted upon a shaft, 12, which may be a countershaft driven 45 from any other convenient shaft, as the cam shaft, 12^a, the showing of these parts in the drawings being intended to be understood as diagrammatic only. The diaphragm chamber, 7, is mounted in a pipe line be- 50 tween two check valves, 13 and 14, both opening in the same direction, the pipe line to the valve, 13, leading from a low-level storage tank, 16, and pipe line from the check valve, 14, leading upward and turn- 55 ing down for discharge into the top of the receptacle, 1. At each rotation of the shaft,

12, the resulting displacement of the diaphragm in one direction will first produce a partial vacuum in the diaphragm chamber, tending to lift the oil from the low 60 storage tank past the check valve, 13, and the opposite displacement will force the oil on past the check valve 14, eventually lifting it high enough for discharge into the receptacle, 1.

To avoid the necessity of keeping watch 65 of the liquid level in the receptacle, 1, and prevent it from being filled to over-flowing, a vent tube, 15, is provided, leading from the diaphragm chamber, 7, to the upper end 70 of the receptacle, 1, and this vent tube is normally closed, preferably outside the receptacle, by a valve, 17, attached to an arm, 18, which carries a float, 19, in the receptacle, which float operates normally as a weight to 75 hold the valve seated; but when the liquid level in the receptacle, 1, rises so as to partly submerge the float, it is lifted and opens the valve, venting the diaphragm chamber so that no pumping action results from the vibration of the diaphragm. When the level 80 of the liquid in the receptacle falls so as to permit the valve, 17, to become again seated, the vibration of the diaphragm operates as before, to pump the oil from the main supply tank to the receptacle, 1. In order that 85 this device may not tend to cause a rapidly fluctuating level of liquid in the receptacle, but, on the contrary, may permit and tend to cause a considerably wide range between the 90 high and low levels at which respectively the valve is opened and closed, it is only necessary to give the port which said valve closes an area sufficient to render the suction on the valve tending to hold it seated great 95 enough to require a predetermined depth of submergence of the float to develop upward pressure enough thereon to force the valve off its seat, by making the float in the form of a comparatively long and slender cylinder 100 as illustrated, a comparatively small area of the port will require considerably deep submergence of the float to force the valve off the seat; and a corresponding fall of level 105 of the liquid will be necessary to again cause the valve to reach its seat so as to experience the suction and be held on the seat. This feature, relatively large vertical and small horizontal dimensions of the float, is claimed in my copending application, Serial No. 110 847,420, filed simultaneously herewith. It 110 will be obvious that the described action of

the pumping device is not dependent upon its being of the diaphragm type, and other well known forms of pump may be substituted without departing from the invention; but, the advantages of a diaphragm pump are obvious, especially when the situation and space available are adapted for relatively large area and short stroke of the back-and-forth moving member of the pump, and also because of the importance of having no air leakage whatever past said member. It will be obvious also that the operation will be in all essential respects similar if the liquid pumped is other than the fuel oil, and if the device supplied is something other than the carbureter. Lubricating oil, for example, may be supplied in the same way to an elevated receptacle, from which it may flow by gravity to the place of service; and I do not, therefore, regard this invention as limited to the one use shown and described.

In the form shown in Fig. 3, the pumping device represented is of the piston type, and it is actuated by connection with the engine exhaust valve, devices being provided in the connection for reducing the speed so that the pump stroke shall not be so rapid as to cause the operation to be defeated by the inertia of the liquid which is to be moved. In this form there is a pump cylinder, 30, of which the intake and discharge is at the lower end, the piston, 31, reciprocating in the upper open end. The cylinder communicates through the head by a passage, 33, of relatively small diameter, but long enough to contain what one piston stroke will draw, with the pipe line or other conduit which connects the main supply tank with the elevated fuel receptacle intermediate the two check valves, 13 and 14, therein. The piston, 31, is connected for reciprocation by a pitman, 35, with the crank wrist, 36, of a crank shaft, 37, on which there is a ratchet wheel, 38, rotated by means of a pawl, 39, which is connected with the stem of the engine exhaust valve. The usually rapid action of the exhaust valve gives, by means of the pawl-and-ratchet wheel connection, a relatively slow rotation to the crank shaft and reciprocates the piston for pumping at a relatively slow speed, which is necessary in order to obtain the flow desired of liquid in the pipe line between the tank and receptacle; for it will be understood that the inertia of the liquid to be moved in the pipe line would prevent it from responding promptly by movement through the pipe line to a very rapid action of the piston, because in such rapid action the resiliency of the air moved by the piston would prevent the liquid from following positively the strokes of the piston, and before the liquid would start upon the drawing or forcing stroke of the piston, 65 the reverse stroke would be reached, the air

cushion between experiencing all the effect of both strokes without transmitting any substantial movement to the liquid. From this arises the necessity for reducing the speed of the piston from that of the exhaust valve when the latter is used as the means of actuating the pump.

I claim:

1. In combination with an automobile engine, a low level liquid supply tank, an elevated liquid receptacle, a pipe line connecting them; two check valves in the pipe line, both opening for flow toward said receptacle, and adapted to be seated by flow in the opposite direction; a pump chamber set off from the pipe line and communicating therewith between said two check valves; a back-and-forth vibrating member which exteriorly closes said pump chamber, and exteriorly connected means for operating said back-and-forth moving member, the capacity of the connecting passage from the pump chamber to the pipe line being as great as the displacement of the vibrating member at each stroke.

2. In combination with an internal combustion engine of an automobile, a low level main storage tank and a higher level receptacle for liquid, a pipe line connecting them; two check valves in the pipe line opening for flow from the main tank to the elevated receptacle and adapted to be closed by flow in the opposite direction; a chamber communicating with the pipe line intermediate the check valves; a diaphragm exteriorly closing said chamber and connections operated by the engine outside the chamber for vibrating the diaphragm, the capacity of the connecting passage from the pump chamber to the pipe line being as great as the displacement effected by each vibration of the diaphragm.

3. In combination with a motor requiring oil for any purpose; a low level main supply tank; a receptacle located at a level from which oil required by the engine may be supplied thereto by gravity; a pipe line connecting the main supply tank and the elevated receptacle; two check valves in the pipe line; a pump chamber communicating with the pipe line intermediate the check valves and extending higher than its said communication; a back-and-forth moving member which closes said pump chamber beyond said higher-extending portion thereof, whereby an air piston is obtained between said back-and-forth moving member for directly actuating the liquid by the movement of said member, and exteriorly connected means for giving back-and-forth movement to said member.

4. In combination with an engine requiring oil, a main oil supply tank located at a low level; a receptacle located at a level from which the oil required by the engine

- may be supplied thereto by gravity; a pipe line connecting the main supply tank with the elevated receptacle; two check valves in the pipe line opening for flow toward the receptacle and adapted to be closed by flow in the opposite direction; a pump chamber communicating with the pipe line intermediate the check valves; a back-and-forth moving member which closes said pump chamber at the side opposite its communication with the pipe line; exteriorly-connected engine-operated means for giving back-and-forth movement to said member; an air vent pipe leading from the pump chamber to the vicinity of the elevated receptacle; a normally closed valve for controlling the entrance of air to said vent pipe, and a float in the receptacle adapted to be operated by the liquid contents thereof at a pre-determined high level of said liquid for opening said valve.
5. In combination with an engine requiring oil, a main oil supply tank at a low level; a receptacle located at a level from which the oil required by the engine may be supplied thereto by gravity; a pipe line connecting the main supply tank with the elevated receptacle; two check valves in the pipe line opening for flow toward the receptacle and adapted to be closed by flow in the opposite direction; a pump chamber communicating with the pipe line intermediate the check valves; a back-and-forth moving member which closes said pump chamber at the side opposite its communication with the pipe line; exteriorly-connected engine-operated means for giving said member its back and forth movement; an air inlet pipe leading from the pump chamber to the vicinity of the elevated receptacle; a valve for controlling entrance of air to said inlet pipe positioned for being held on its seat by the suction through said pipe; a device buoyed by the liquid in the receptacle, and connections from said buoyed device for forcing said valve off its seat against said suction upon a pre-determined submergence of said buoyed device.
6. In combination with an engine requiring oil, a main oil supply tank at a low level; a receptacle located at a level from which the oil required by the engine may be supplied thereto by gravity; a pipe line connecting the main supply tank with the elevated receptacle; two check valves in the pipe line opening for flow toward the receptacle and adapted to be closed by flow in the opposite direction; a pump chamber communicating with the pipe line intermediate the check valves; a diaphragm closing said pump chamber at the outer side; exteriorly-connected engine-operated means for vibrating the diaphragm, an air vent pipe leading from the pump chamber to the vicinity of the elevated receptacle; a normally closed valve for controlling the entrance of air to said vent pipe, and a float in the receptacle adapted to be operated by the liquid contents thereof at a pre-determined high level for opening said valve.
7. In combination with an engine requiring oil, a main oil supply tank at a low level; a receptacle located at a level from which the oil required by the engine may be supplied thereto by gravity; a pipe line connecting the main supply tank with the elevated receptacle; two check valves in the pipe line opening for flow toward the receptacle and adapted to be closed by flow in the opposite direction; a pump chamber communicating with the pipe line intermediate the check valves; a diaphragm closing said pump chamber at the outer side; exteriorly-connected engine-operated means for vibrating the diaphragm; an air vent pipe leading from the pump chamber to the vicinity of the elevated receptacle and which communicates with the pump chamber; a valve for controlling the entrance of air to said vent pipe positioned for being held on its seat by the suction through said pipe; a device buoyed by the liquid in the receptacle, and connections therefrom for forcing said valve off its seat against the suction upon the pre-determined submergence of said device.
- In testimony whereof, I have hereunto set my hand at Chicago, Illinois, this 24th day of June, 1914.

WEBB JAY.
